SCUBA DIVING DEVICE

Myron A. Kenney, 415 Marquette St.,
Bay City, Mich. 48706

Filed Mar. 28, 1969, Ser. No. 16,515

Term of patent 14 years

Int. Cl. D21—03

U.S. Cl. D71—1

FIG. 1 is a side elevational view of my scuba diving device;

FIG. 2 is a top plan view thereof;

FIG. 3 is a rear elevational view; and

FIG. 4 is a front elevational view.

I claim:

The ornamental design for a scuba diving device, substantially as shown and described.
